Meyers, Cushman & Rea

UNITED STATES PATENT OFFICE.

INGENUIN HECHENBLEIKNER, OF CHARLOTTE, NORTH CAROLINA, ASSIGNOR TO SOUTHERN ELECTRO-CHEMICAL COMPANY, OF NEW YORK, N. Y., A CORPORATION OF NEW JERSEY.

METHOD OF AND APPARATUS FOR PRODUCING GASES.

1,409,295.

Specification of Letters Patent. Patented Mar. 14, 1922.

Application filed October 6, 1919. Serial No. 328,692.

To all whom it may concern:

Be it known that I, INGENUIN HECHENBLEIKNER, a citizen of the United States, residing at Charlotte, in the county of Mecklenburg and State of North Carolina, have invented new and useful Improvements in Methods of and Apparatus for Producing Gases, of which the following is a specification.

- 10 The present invention relates to a method of and apparatus for producing gases, and is in the nature of an improvement upon the inventions forming the subject matter of my earlier United States Patents, Nos. 1,167,755; 15 1,299,336; and 1,299,337. By reference to these earlier patents the purpose of my present invention, as hereinafter described, will be readily understood. For example, by means of the apparatus constituting the subject matter of Patent 1,299,336, I have heretofore practiced the method set forth in companion Patent 1,299,337, that is to say, I have subjected a mixture or charge of phosphate rock and a silicious material containing potash and a proper proportion of carbonaceous material to the action of an electric furnace to generate certain gases or vapors which were subsequently oxidized and purified, the purified vapors being subsequently further treated, as well known in the art, to obtain phosphoric acid and potash. The mixture I usually employ in the production of the gases is composed of feldspar, calcium phosphate and coke.
- 25 30 35 The apparatus shown in Patent 1,299,336 embraces an electric furnace having a mixing chamber communicating therewith and an inclined rotary kiln connected with the mixing chamber. Certain components of the charge, such as the feldspar and calcium phosphate are fed into the kiln at a point distant to the mixing chamber, and travelling through substantially the length of the kiln pass into the mixing chamber where 40 45 50 they are mixed with the coke and forced into the electric furnace. The gases issuing from the furnace pass upward and outward through the kiln thus meeting and preheating the downcoming charge, all as will be readily understood by reference to said Patents 1,299,336 and 1,299,337.

However, I have found, in using the above mentioned apparatus, and practicing the before referred to method that certain difficulties are encountered in manufacturing upon a large commercial scale which requires continuous operation. One difficulty is that there is a distinct tendency for certain impurities in the outflowing gases to condense at the mouth or discharge end of the kiln, thereby forming a crust or accumulation which gradually increases in size and thickness, and which if not removed from time to time will ultimately choke or close the discharge end of the kiln thereby preventing the feeding of the charge to the furnace and also interfering with the free outflow of the gases. It is a difficult task to remove this crust by means of a crowbar or other tool in the hands of a workman because of the intense heat at this portion of the apparatus, and therefore it is frequently necessary to shut down the apparatus, or discontinue operation, in order to permit of the cleaning away of the accumulated crust. Naturally such shutting down or cessation of operation curtails the output and is expensive so that if possible it should be avoided.

With my present invention I prevent the formation of this crust or accumulation at the discharge end of the kiln thus avoiding the disadvantages above recited.

Briefly, I accomplish this object by introducing a fluid, such as a stream of water or steam, into the discharge end of the kiln. This fluid prevents the formation of the crusts and maintains the discharge end of the kiln clean and clear of all accumulations of foreign substance. Furthermore, by the use of such fluid, I accomplish another desirable purpose in that it enables me to regulate the heat at the discharge end of the kiln thereby preventing the lumping or liquefying of the material flowing down the kiln— which lumping or liquefying will occur sometimes under the action of excessive heat. When it does occur the steady and free feed of the material into the mixing chamber and furnace will not take place. However, by the use of the fluid, such as water or steam, the material of the charge is maintained in a free-flowing condition and will readily pass or discharge into the mixing chamber and furnace.

The amount of the fluid, such as water or steam, which I employ will depend of course upon the capacity of the furnace and kiln,

and may be regulated in any suitable manner as by valves or the like to obtain desired working conditions.

With the above recited objects and others of a similar nature in view my invention consists in the improved apparatus and in the method set forth in and falling within the scope of the appended claims.

In the accompanying drawings:

Figure 1, is a view partly in vertical longitudinal section and partly in elevation of an apparatus embodying my invention.

Figure 2, is an enlarged vertical sectional view of a portion of the apparatus where 15 the rotary kiln discharges the charge into the mixing chamber of the furnace.

Figure 3, is a horizontal sectional view of such a portion of the apparatus.

Referring now to the accompanying drawings in detail, the letter A indicates the electric furnace and B the mixing chamber thereof, while C is the rotary kiln, inclined to the horizontal, and communicating at its lower end with the mixing chamber and mounted at its upper end upon the neck D communicating with the dust collector E, the kiln of course being arranged to rotate. Certain components of the charge, such as the feldspar and calcium phosphate may be fed through the hopper F to the kiln and so passed down through the kiln into the mixing chamber where these components are mixed with coke and discharged into the electric furnace by means of a suitable stoker conventionally illustrated at G. The electrodes of the furnace are indicated at H while I is an air inlet and J is a suction fan for drawing the gases through the kiln and dust collector. All of these parts of the apparatus are shown and described in my aforesaid Patent 1,299,336, and are therefore but briefly referred to here.

To prevent the formation of a crust by the condensation of impurities in the gases, as before mentioned, I provide a pipe or pipes K which lead from a suitable source of fluid supply, and through which the fluid, preferably water or steam, may be introduced into the mouth or discharge end of the kiln as at K'. Each pipe may be provided with a suitable valve L to regulate the amount of water or steam introduced into the kiln, and also to control or regulate the heat at the end of the kiln so as to prevent lumping or liquefying of the down-coming charge, as heretofore mentioned. I prefer that the fluid, such as the steam or water should be discharged into the mouth or discharge end of the kiln at approximately the point or points shown in the drawing, or relatively near to the mixing chamber, as it is here that the crust is likely to form, but I wish it to be understood that my invention is not

limited to the arrangement, position, or system of the piping shown, as this may be of any suitable character to suit the particular requirement and peculiarities of construction of the apparatus in use. I 70 wish it to be further understood that the invention is not limited to use in connection with the particular type of apparatus shown in my earlier patents aforesaid, as it may be used in connection with any apparatus or system wherein it is useful to prevent the formation of crusts or accumulations and to maintain a fed charge material in proper condition under circumstances like those heretofore mentioned. 80

What I claim is:

1. An apparatus including a furnace, means for conducting gas producing material to the furnace, and means at a point therein operative for supplying a fluid to 85 the conducting means to prevent crustation and accumulation of foreign substances in the conducting means.

2. An apparatus including a furnace and a kiln communicating therewith and from 90 which kiln gas producing material is adapted to be discharged into the furnace, and means for discharging a fluid into the kiln at a point adjacent the furnace operative to prevent crustation and the accumulation 95 of foreign substances in the kiln.

3. An apparatus including an electric furnace and a rotary kiln communicating with the furnace and through which kiln a charge of gas producing material is adapted to pass 100 into the furnace, and means for supplying a fluid to the kiln at a point therein operative to prevent accumulation of foreign substances in the kiln and to maintain the material in a free flowing condition. 105

4. An apparatus including a furnace and a kiln from which kiln gas producing material is adapted to pass to the furnace, and piping communicating with the interior of the kiln adjacent the furnace to introduce 110 water or steam into the kiln operative during operation of the kiln to prevent an accumulation of foreign substances in such kiln.

5. An apparatus including a furnace, 115 means for conducting gas producing material to the furnace, and means for supplying a fluid to the conducting means at a point therein operative during the normal operation of the furnace to prevent crustation and 120 accumulation of foreign substances in the conducting means.

6. The herein-described method which consists in feeding a gas producing charge into a furnace, and introducing a fluid into the 125 path of the moving charge at a point in the said path to prevent crustation and to maintain the material in a free flowing or feeding condition.

7. The herein-described method which con- 130

sists in feeding a gas producing charge into a furnace, and introducing water or steam into the path of the moving charge at a point in the said path to prevent crustation and to maintain the material in a free flowing or feeding condition.

8. The step in the method of feeding a gas producing charge into a furnace, which

consists in introducing adjacent the furnace a fluid into the path of the moving charge to prevent crustation and to maintain the charge in free flowing or feeding condition adjacent the furnace.

In testimony whereof I have hereunto set my hand.

INGENUIN HECHENBLEIKNER.
